UNITED STATES PATENT OFFICE.

IRA E. STUMP, OF CLEVELAND, OHIO.

SELF-CLOSING FAUCET.

Application filed October 11, 1922. Serial No. 593,707.

To all whom it may concern:

Be it known that I, IRA E. STUMP, a citizen of the United States, residing at Cleveland, in the county of Cuyahoga and State 5 of Ohio, have invented certain new and useful Improvements in Self-Closing Faucets, of which the following is a specification.

My invention relates to improvements in self-closing valves such as self-closing faucets, basin cocks, and the like.

The present embodiment relates more particularly to a self-closing faucet for use in connection with basins or lavatory bowls, but it should be understood that the improvements 15 may be readily incorporated in or adapted to various forms of bibs, cocks or faucets.

The primary object of my invention is to provide a generally improved self-closing 20 valve or cock of the class indicated which will be exceedingly simple in construction, cheap of manufacture and efficient in use.

A further and very important object is the provision of a self-closing valve of this class 25 having its various working parts so arranged and disposed as to permit of the ready removal of the main valve and valve actuating stem or spindle without the necessity of turning off the water in the pipe 30 or supply line below the valve or faucet, an improved secondary valve and valve chamber being provided which will automatically cut off the flow of water through the valve or faucet when such parts are removed.

A still further and very important object 35 is the provision of an improved self-closing faucet of this class having a removable housing forming the secondary valve chamber and the main and secondary valve seats 40 whereby such seats may be readily reground and whereby such secondary valve and valve seat forming member or housing may be readily removed or adjusted through the opening in the valve body or casing when 45 the bonnet and cap and operating spider are removed.

A still further object is the provision of 50 an improved cock or faucet in which the liability of breakage or disarrangement of the parts is reduced to a minimum and in which the valves are fully opened or closed through a quarter turn of the crown wheel or handle and in which upon the release of such crown wheel or handle the valve parts will immediately return to closed position.

A still further object is the provision

of a valve in which the parts are so arranged and disposed as to follow a true centralized position in the opening and closing movement and in which the parts will 60 be maintained in a true seated position to prevent leakage.

With the above mentioned and other ends in view, the invention consists in the novel construction, arrangement and combination 65 of parts, hereinafter described, illustrated in some of its embodiments in the accompanying drawings and particularly pointed out in the appended claims.

Referring to the drawings, forming a part 70 of this specification, Figure 1 is a side elevation, partly in central longitudinal section, of a self-closing faucet constructed in accordance with this invention, the parts being in a closed position.

Fig. 2, a similar view, the parts being in 75 open position.

Fig. 3, a fragmentary side elevation of the rotary valve actuating member or spider, detached, and illustrating in particular the 80 oppositely arranged inclines for receiving and engaging the oppositely arranged projections on the reciprocatory valve actuating stem.

Fig. 4, a similar view of the same turned 85 a quarter turn, or at right angles to the position shown in Fig. 3.

Fig. 5, a top plan view of the bonnet, detached, and illustrating in particular the 90 guide-ways for the projections of the reciprocatory valve stem and the central bearing for the rotary valve actuating spider.

Fig. 6, a side elevation of the same.

Fig. 7, a side elevation of the reciprocatory 95 valve actuating stem or spindle detached.

Fig. 8, a top plan view of the main valve disc and gasket detached from the valve stem.

Fig. 9, an edge view of the same.

Fig. 10, a top plan view of the valve seat 100 forming secondary valve housing, detached, and illustrating in particular the annular seat for the main valve and the secondary passage leading thereto.

Fig. 11, a side elevation of the same.

Fig. 12, a top plan view of the secondary 105 valve, detached.

Fig. 13, a side elevation of the same.

Fig. 14, a fragmentary vertical central 110 sectional view of a faucet or valve housing equipped with a modified form of valve seat forming secondary valve housing.

Similar numerals of reference designate like parts throughout all the figures of the drawings.

The valve body or faucet casing 1, may be of any suitable and convenient construction and when used as a bib cock or faucet is provided with a suitable bib or spout 1^a. The body or casing 1 is provided, in the present instance, with a suitable base flange 1^b, and a suitable extension 1^c, provided with threads for attachment to the supply pipe. The valve or faucet body is provided with a main inlet passage or port 1^d, terminating in an annular secondary valve seat 1^e. The passage or port 1^d terminates in a secondary valve chamber 1^f, which may either be formed in the body itself, as shown at 1^g in Fig. 14 of the drawings, or such secondary valve chamber may be formed within the base portion of a valve seat forming member or secondary valve housing 2, as shown in Figs. 1, 2, 10 and 11 of the drawings.

As a means of conveniently inserting or removing the secondary valve hereinafter referred to, and particularly as a means of readily regrinding or of adjusting the valve seats for the main and secondary valves or of inspecting or replacing the parts, the valve seat forming member 2 is threaded to connect with a similarly threaded portion in the base of the casing 1, as shown. The main valve seat forming member 2^a, arranged above the valve housing 2, is provided with a secondary passage or port 2^b, connecting the annular secondary valve seats 2^c and 2^d. The valve seat 2^c is preferably bevelled or counter-sunk, as shown, and the valve seat 2^d is preferably raised or of ring shape for affording a firm seat for the main valve hereinafter referred to.

The secondary valve chamber 1^f is provided with a secondary valve 3, adapted to operate between the valve seats 1^e and 2^c, said secondary valve 3 being preferably of square or angular form, as shown most clearly in Fig. 12 of the drawings, so as to provide passages for the inlet of the water when such valve is raised in view of the round or cylindrical walls of the valve housing 2.

As shown in Fig. 2 of the drawings when the main and secondary valves are in their open positions, the secondary valve is held down by the stem portion of the main valve and such secondary valve will not close the secondary passage 2^b, the closing of such secondary passage taking place automatically through the pressure of the liquid or water when the main valve and operating mechanism are removed.

The secondary valve 3 is preferably provided with an annular seat portion 3^a, and is provided with an upwardly extending projection 3^b, to enter the secondary passage 2^b, as shown in the drawings.

As a means of providing a separate but

operable connection with the secondary valve 3 and providing for the ready removal of the main valve and valve operating stem and bonnet when desired, the bonnet 4, is provided with a central stem receiving opening 4^a, adapted to receive and contain a reciprocating valve stem 5, the latter being provided at its lower end with a valve head 5^a, said head terminating in a central stem portion 5^b, adapted to extend through the secondary passage 2^b and to engage with and cooperate with the projection 3^b of the secondary valve 3. The stem 5^b and head 5^a are adapted to removably receive and carry a removable valve comprising a disc 5^c, and a washer 5^d, of suitable resilient material such as felt or fiber or rubber composition.

As a means of causing the main valve, designated generally by the numeral 5^a, to return to and to be maintained in seated position upon the valve seat 2^d when opening pressure or movement on the operating handle and spider is released, the main valve is adapted to operate against the resistance of a spring 6, surrounding the valve stem 5^b and abutting against the central portion of the bonnet 4.

As a means of permitting longitudinal and preventing circumferential movement of the valve stem 5 when the latter is actuated by the rotary actuating member or spider, hereinafter referred to, the valve stem is provided with oppositely arranged projections 5^e, in the present instance, being formed by means of a cross pin, said projections 5^e, being guided in oppositely arranged guide slots 4^b in the bonnet.

The bonnet 4 is provided with a central bearing portion 4^c, forming a cylindrical guide bearing portion adapted to removably receive and carry a valve actuating rotary member or spider 7.

The spider 7, is provided with oppositely disposed cam or wedge shaped members 7^a, connected by means of arms 7^b, said members 7^a being provided with oppositely arranged inclines 7^c, adapted to cooperate with and travel beneath the projections 5^e, so that when the valve actuating member 7 is moved to the right or left through the medium of the crown wheel 8, such inclined portions 7^c will elevate the stem 5. Upon such elevation of the stem 5 and the main valve 5^a against the resistance of the spring 6, and as carried by the liquid or water pressure in the main passage 1^d, it will be obvious that the main and secondary valves will be moved from their seats to provide an outlet passage for the water as indicated by the arrows in Fig. 2 of the drawings. Upon the release of the crown wheel or handle it will be seen that the inclination of the inclines 7^c relative to the projections 5^e is such that the spring action of the spring will automatically return the valves to their seats and therefore

close off any further flow of water. The rotary valve actuating member or spider 7 is removably retained in place upon the bonnet by means of a cap 9, having a central opening 9^a, to receive the stem or spindle portion 7^a of the rotary actuating member which is provided with the crown handle or wheel.

Having thus described one of the embodiments of my invention, without having attempted to set forth all the forms in which it may be made, or all the modes of its use, what I claim and desire to secure by Letters Patent is,—

1. In a faucet, a faucet body provided with 15 communicating main and secondary passages, an adjustable member in said faucet body provided with main and secondary valve seats, relatively movable main and secondary valves controlling said passages in 20 cooperative relation to said seats, a valve stem carrying said main valve and engaging and moving said secondary valve against water pressure when moved in a closing direction, and means for raising and lowering 25 said stem and main valve.

2. In a self-closing faucet, a faucet body provided with main and secondary communicating passages and valve seats, main and secondary valves for controlling the flow of 30 fluid through said passages and seats, a valve stem carrying one of said valves to control the flow of fluid through said secondary passage and the main valve seat and to operate said secondary valve against the pressure of 35 water, a spring acting to move said valve stem and main valve against the pressure of the water in said passages, means for adjusting said valve seats, and means for reciprocating said stem against the resistance of 40 said spring.

3. In a self-closing faucet, a faucet body provided with main and secondary communicating valve chambers and valve seats, main and secondary valves in said chambers 45 in cooperative relation to said seats, a valve stem carrying said main valve and separate from and adapted to engage and actuate said secondary valve, a spring for closing said main valve against liquid pressure, a bonnet provided with guide-ways receiving 50 said stem, and a rotary member having slideable engagement with said stem whereby said valve stem is moved longitudinally against the resistance of said spring.

55 4. In a valve, a valve body having an annular valve seat, a secondary valve vertically movable in a valve chamber in cooperative relation to said valve seat, a main valve, an adjustably mounted valve housing forming 60 said valve chamber and having a valve seat which is adapted to be closed by said secondary valve when the latter is left free by the removal of said main valve, a vertically movable valve stem carrying said main 65 valve, and means for raising said main

valve and stem and controlling the movement of said secondary valve through the movements of said main valve stem.

5. In a self-closing faucet, a faucet body including main and secondary communicating passages and valve seats, main and secondary valves in cooperative relation to said passages and seats, a spring resisted valve stem adapted to actuate said main and secondary valves, a bonnet permitting longitudinal and preventing circumferential movement of said valve stem, a rotary member on said bonnet operatively connected to said stem to move the latter against the resistance of said spring, the arrangement between said stem and rotary member being such as to permit the parts to automatically return and close said valves through said spring upon the release of said rotary member.

6. In a self-closing faucet, a faucet body including communicating main and secondary passages, main and secondary valves adapted to open and close said passages, a spring resisted valve stem for actuating said main and secondary valve, a bonnet permitting longitudinal and preventing circumferential movement of said valve stem, a rotary member on said bonnet having opposite inclines connected to and operating said stem against the resistance of said spring, the inclined connections between said stem and rotary member permitting the valves to automatically return and close said passages upon the release of circumferential pressure on said rotary member.

7. In a self-closing faucet, a faucet body including main and secondary communicating passages and chambers and valve seats, main and secondary valves in said chambers 105 in cooperative relation to said passages and seats, a spring resisted valve stem carrying said main valve and adapted through its movement to open and close said main valve with and against the pressure of the liquid 110 in said secondary passage, respectively, said stem adapted to close said secondary valve against the pressure of the liquid and a bonnet permitting longitudinal and preventing circumferential movement of said valve 115 stem, said bonnet being provided with a rotary member having inclines adapted when moved circumferentially to elevate said stem and main valve against the resistance of said spring and to permit said main valve 120 to move to normal or closed position upon release of said rotary member.

8. In a valve, a valve body having a main inlet passage, a removable valve housing in said valve body forming a secondary valve 125 chamber, a secondary valve in said inlet passage and chamber, said valve housing being provided with a second inlet passage and opposite valve seats, one of which is adapted to be automatically closed by said secondary 130

valve through water pressure when the main valve is released by the removal thereof, a vertically movable valve stem carrying said main valve and adapted to open and close 5 said secondary inlet passage through the opening and closing movements thereof, and means for raising and lowering said valve stem and main valve.

9. In a self-closing faucet, a faucet body 10 including main and secondary communicating passages and chambers and valve seats, main and secondary valves in said chambers in cooperative relation to said valve seats, a spring resisted valve stem carrying said 15 main valve and adapted to engage and open said secondary valve against the pressure of the liquid in said main passage, and a bonnet permitting longitudinal and preventing circumferential movement of said valve stem, 20 said bonnet being provided with a rotary member having cam members adapted when moved circumferentially to elevate said stem against the resistance of said spring to open said main valve and to permit the same to 25 be moved to valve closing position by said spring upon release of circumferential pressure on said rotary member.

10. In a valve, the combination with a 30 valve body having main and secondary communicating valve chambers and passages; of main and secondary valves in said chambers adapted to open and close said secondary and main passages, a spring resisted valve stem having guides and carrying said main 35 valve to close said secondary valve against the water pressure, a bonnet on said valve body provided with guide slots receiving said guides to permit longitudinal and prevent circumferential movement of said valve 40 stem, and a relatively movable spider surrounding said valve stem having inclines in cooperative relation to said guides on said valve stem to move said stem longitudinally when moved circumferentially against the 45 resistance of said spring and to permit the latter to move said main and secondary valves to closed positions when said spider is released.

11. In a self-closing faucet, a faucet body 50 provided with main and secondary communicating valve chambers and passages and valve seats, main and secondary valves in said chambers in cooperative relation to said 55 passages and seats, a valve stem having opposite projections and carrying said main valve and adapted to positively operate said secondary valve in valve closing direction, a spring for normally closing said main and secondary valves against liquid pressure, a 60 bonnet provided with guideways receiving said opposite projections formed on said stem, and a rotary member having opposite inclines riding under said projections where- 65 by said valve stem is moved longitudinally against the resistance of said spring when

said rotary member is moved in either direction and said rotary member is moved to a valve closing position automatically by the action of said spring and said valves are closed when said rotary member is released. 70

12. In a valve, the combination with a valve body having main and secondary communicating valve chambers and passages and main and secondary valve seats; of main and secondary valves in said chambers 75 adapted to open and close said passages, respectively, a spring resisted valve stem having projections and carrying said main valve and adapted to close said secondary valve against the water pressure, a bonnet on said valve body provided with guides operatively connected to said stem and permitting longitudinal and preventing circumferential movement thereof, and a circumferentially 80 movable spider surrounding said valve stem and having cams in cooperative relation to said projections to move said stem longitudinally when said spider is moved circumferentially in one direction against the resistance of said spring and to permit the stem to close said main and secondary valves when moved in an opposite direction. 85

13. In a faucet, a faucet body provided with main and secondary communicating 90 passages and adjustable valve seats, main and secondary valves controlling the flow of fluid through said passages, a valve stem for controlling the movement of said secondary valve and adapted to operate said main and secondary valves against water 95 pressure in said passages, and means for raising and lowering said valve stem. 100

14. In a faucet, a faucet body provided with main and secondary communicating 105 passages and a removable valve housing member provided with valve seats, main and secondary valves for said seats, said secondary valve being arranged in said valve housing member, a valve stem carrying said main valve and adapted when moved to a 110 closed position to positively close said secondary valve against water pressure, and means for raising and lowering said valve stem and main valve.

15. In a faucet, a faucet body provided with communicating main and secondary 115 passages, a removably and adjustably mounted member within said faucet body provided with main and secondary valve seats, separate main and secondary valves for controlling the flow of fluid through said 120 passages in cooperative relation to said seats, a valve stem carrying said main valve adapted to close said secondary valve against water pressure when moved to a closed position, and means for raising and lowering said valve stem. 125

16. In a faucet, a faucet body provided with superposed main and secondary communicating passages and seats, superposed 130

main and secondary valves for said seats, a valve stem for positively opening and closing said main valve and for coming into engagement with and positively moving said secondary valve against water pressure toward a closed position when said main valve is moved from its fully open to an intermediate position and for positively closing said secondary valve on one of said seats when said main valve is closed, and means for raising and lowering said stem and main valve and for removing the latter independently of said secondary valve. 10

In testimony whereof I have affixed my signature.

IRA E. STUMP.
